(57) **CLAIM**

The ornamental design for a cup for a juice extractor, as shown and described.

DESCRIPTION

FIG. 1 is a perspective view of a cup for a juice extractor showing our new design.

FIG. 2 is a front view thereof.

FIG. 3 is a rear view thereof.

FIG. 4 is a left side view thereof.

FIG. 5 is a right side view thereof.

FIG. 6 is a top plan view thereof.

FIG. 7 is a bottom plan view thereof; and,

FIGS. 8A and 8B are two separate reference views of a cup for a juice extractor in order to show a use state thereof.

The broken lines in the figures are for illustrative purposes only and form no part of the claimed design.
